64. **TYPE-WRITING MACHINE.**

1,169,323.

Specification of Letters Patent. Patented Jan. 25, 1916.

Application filed March 20, 1913. Serial No. 755,586.

To all whom it may concern:

Be it known that I, ADOLPHUS S. DENNIS, a citizen of the United States, residing in Lakewood, in the county of Cuyahoga and 5 State of Ohio, have invented certain new and useful Improvements in Type-Writing Machines, of which the following is a specification.

This invention relates to work-holding or 10 feeding devices of typewriting machines.

One of the objects of the invention is to provide for proper holding and feeding of cards or narrow sheets, and particularly with a view to facilitating the writing near 15 the edges of said cards, and especially the side and bottom edges of said cards or sheets.

In the machine illustrated herein, the side edges of the work-sheets are held against the platen by means of thin flexible bands 20 which are taunted against the platen and are adjustable along the same to accommodate the width or position of the work-sheet, these bands extending from below to above the printing line and each band being caught 25 at both top and bottom ends; a pressure roll being also preferably provided at the top of each band to run upon the platen. I also provide upon the machine frame paper-guides, one at each side of the usual central type 30 guide. These guides are of substantial length, so that the card or work-sheet may be successfully held, and of a width varying from, say two to eight or more inches; the frame guides serving to hold the bottom 35 edge of the card or sheet against the platen, while the flexible bands hold the side edges thereof against the platen, so that the sheet may always have a firm backing where it receives the type impressions. These frame 40 guides may be provided with scale marks so that they thus act as gages; and in order to avoid difficulty from the work-sheet jumping above the frame guides when the platen is shifted up to print capital letters, during 45 the writing of the last line on the work-sheet, I arrange to shift the frame guide, gages or scales up and down with the platen. These frame guides or gages normally register with the bottom of the printing line on the platen, 50 and owing to their length, they collide with the ends of the platen carriage when they are shifted up with the platen for writing capital letters. In order to avoid trouble from

such collision, the outer ends of the frame guides are beveled, so that the carriage end 55 operates to force the guides down, so that no harm results.

The side bands are arranged to slip between the frame guides and the platen and also between the usual ribbon vibrator and 60 the platen. It will be seen that by reason of all these provisions, a successful card guide is produced, which may be incorporated in the machine and will serve all paper-guiding purposes as well as being practical for card-guiding. The invention moreover has the 65 advantage of being inexpensive and simple, and readily applicable to existing machines.

In the accompanying drawings, Figure 1 is a front elevation of a platen and paper carriage of an Underwood front-strike typewriting machine embodying my present improvements; the parts being shown in lower-case positions. Fig. 2 is a similar view showing the parts shifted up to upper-case positions. Fig. 3 is a sectional side elevation showing a type about to strike the platen; the parts being in the same position as at Fig. 1. Fig. 4 is a perspective view of a guard or shield used at the back of the ribbon to prevent fouling of the same with the guide bands for the side edges of the sheet. Fig. 5 shows the platen shifted up for printing capital letters, together with the frame guide, gage or scale, etc. Fig. 6 is a perspective view of one of the shiftable carriers on which a frame guide, gage or scale is mounted. Fig. 7 is a perspective view of one of the frame guides, gages or "wing" scales. Fig. 8 shows a bracket which is intended for mounting on the usual type bar segment to carry a linkage for one of the frame guides or "wing" scales. Fig. 9 is a view to illustrate how the carriage end cams down the frame guide or scale from the dotted line to 90 the full line position (independently of the opposite guide or scale) as the carriage moves in letter-feeding direction.

In the Underwood typewriting machine, types strike against the front side of a revoluble platen 2, which is mounted by an axle 3 in the ends 4 of a platen frame, which comprises a paper-shelf 5 and has on its side the usual releasable front and rear bottom feeding rolls 6, 7. The types are provided on the 105 usual type-bars which are mounted in the

usual manner on the type-bar segment 42, illustration of the actual mounting being, however, omitted.

- Upon the front of the platen run pressure rolls 8 which are similarly mounted and operated, and which serve as feeding rolls for the work-pieces, being of special value for this when the work-piece is beyond the grip of the lower feed rolls. Each roll 8 is journaled upon a mount comprising a pair of arms 9 extending forwardly from a rod 10 around which the mount is adjustable, the arms 9 being connected by a cross-piece 11; and a spring 12 bearing against said cross-piece 11 holds a key 13 in a longitudinal groove 14 in the rod 10 to hold the pressure roll 8 against the platen; said key being guided in slots in said arms 9. Said rod is fastened at its ends to a pair of arms 15 to form a bail which is hinged or pivoted at 16 to brackets 17 fixed by screws 18 upon the platen frame ends 4, said brackets extending down between the platen and the platen frame ends.
- The screw pivots 16 may be concentric with the pivots 19 of the front pressure rolls so that when the rod 10 is swung forwardly out of normal position, the rolls will either remain on the platen or near the same.
- Each mount can be rocked upon the rod 10 to swing the rolls entirely away from the platen, so that the operator has the choice either of swinging the rod forwardly while leaving the rolls on or near to the platen, or else of swinging the mounts and rolls upwardly. There extends downwardly from the lower or forward end of each mount, a short band 20 which is flexible and springy and may consist of a very thin steel spring, although any other material may be used. The lower end of this band may be caught upon a rod 21, which at its ends is fixed in the lower ends of the brackets 17. These bands are held taut against the platen, and this, it will be understood, is done without releasing the pressure of the rolls 8. On the contrary, the pull of the band may augment the pressure of said rolls.
- The bands are efficient paper feeders, and taken in connection with the rolls, make a very satisfactory device for this purpose. The lower ends of the bands may be only slightly hooked around the rod 21, as at 22, and this will permit the bands to be unhooked when it is desired to swing up the arms 9. In order to unhook them, it is only necessary to swing the rod 10 forward a little, and then swing the mounts around the rod. It will be seen that either front paper guide may be adjusted at any time to any position required along the platen. The bands 20, being thin and lying snugly against the platen, readily pass behind the front gages or scales 23, and they may also easily slip behind the usual ribbon 24 and

vibrator 25, and the latter may have guards 26, one at each side of the printing point. The guards may be secured at their lower ends in any suitable manner upon the ribbon vibrator, so as to leave a space between the vibrator and the guards for the introduction of the ribbon; and the guards may, at their upper edges, flare forwardly as at 27, so as to be engaged and cammed backwardly toward the ribbon, to prevent the latter from being caught by said bands.

The "wing" scales 23 serve as guides for the lower edges of the work-sheet, and are intended to hold the work-sheet while a line is written very close to the bottom edge thereof. These guides or gages 23 are mounted to shift up and down with the platen 2. The platen is shifted up and down by means of a shift rail 28 in the usual manner, the platen frame 4 having a rod 29 upon which is mounted a roll 30 to run upon said rail 28 as usual. The rod 21, which of course shifts up and down with the platen, is employed for controlling the rising and falling movements of the guides, gages or scales 23; springs 31 tending constantly to shift said scales, and pins 32 being connected to the scales and extending under said rod 21, whereby the latter holds the scales against rising, but permits the scales to rise when the carriage is shifted up from the position at Figs. 1 and 3 to the position at Figs. 2 and 5. It will be seen that the scales are carried on mounts 33 and that the latter are mounted upon bell cranks 34, 35, one pair at each side of the central type guide; each pair of bell cranks being pivoted to a bracket 41 secured to the usual type-bar segment 42, and being connected by a horizontal link 36, so that the scales move up and down in parallelism. The upper arms of the bell cranks form parallel links connecting the mounts 33 with their support. Each scale is pivoted at 37 to its mount and pressed by a spring 38 rearwardly against the platen or the sheet thereon to hold the sheet against the platen. Whenever the platen is shifted up, the rod 21 is carried up with it and the springs 31 are permitted to throw the links 36 toward each other and thereby swing equally all of the four bell cranks 34, 35, and lift the mounts 33, thus carrying up the scales 23. When the platen drops, the rod 21 acts on the pins 32 to depress the same, carrying down the mounts 33 (from which said pins project) and restoring the other parts to normal lower case positions as seen at Fig. 1. Since the aforesaid rod is mounted in the platen frame, as previously stated, it will partake of the endwise movements of the platen, and will, therefore, have a running engagement with the pins 32. In order to make these "wing" scales of practical value, they must have substantial

length so that they may control the bottom edges of sheets that are nearly the same width as the carriage, and when the scales are made this length, they collide with the carriage ends 39, this occurring because the upper edges of the scales must be high enough to register.

One of the features of the present invention is the provision of means whereby such long scales or guides can be employed notwithstanding the apparent necessity of reducing their measurements to a size accommodated by the length of the carriage itself. This object is accomplished by making the scales compressible by mounting them in the manner aforesaid and bending or beveling their outer ends as at 40, so that when either carriage end 39 engages a scale, it cams down the same to the full line position in Fig. 9 and rides over the top edge of the scale as there shown. The dotted lines show the position of the scale when engaged by the carriage ends, and the full lines show the depression of this scale effected by the carriage ends. Thus a scale of ample transverse measurements may be employed on the machine frame, and hence the machine is rendered suitable for holding wide cards as well as narrow cards firmly against the platen while the same are being written upon close to the bottom edge thereof.

It will be seen that the depression of the scale at Fig. 9 occurs independently of the platen shift frame or of the rod 21, since either pin 32 may have a downward movement away from said rod independently thereof. These scale depressing pins are placed close to the middle of the machine where they are not apt to be struck by the bands 20; and moreover the pins 32 may be made of round contour, so that the bands, where they hook under the rod 21, may pass freely by the pins; these bands being of very thin metal, and hence not displacing either the pins 32 or any of the other parts to any extent on any occasion.

Variations may be resorted to within the scope of the invention, and portions of the improvements may be used without others.

Having thus described my invention, I claim:

1. In a typewriting machine, the combination of a traveling platen; means to shift the platen to upper and lower case positions; a guide supported entirely by the frame of the machine and stationary during the travel of the platen; and means separate from said shifting means for moving said guide up and down with said platen.
2. In a typewriting machine, the combination, with a carriage and a platen movable in letter-feed direction; of a stationary support on the machine frame; a paper guide mounted on said support; means to shift said platen up and down; and means separate

from said shifting means to move said guide up and down with said platen.

3. In a front-strike typewriting machine, the combination of a traveling platen frame and platen shiftable up and down, and a non-traveling guide in front of the platen and operated directly by the platen frame to shift therewith.

4. In a typewriting machine, the combination of a traveling platen shiftable to upper and lower case positions, a non-traveling paper guide in front of the platen, and means traveling with the platen to shift said guide with the platen.

5. In a front-strike typewriting machine, the combination of a traveling platen shiftable to upper and lower case positions, a ribbon vibrator in front of the platen, stationary guides on opposite sides of the ribbon vibrator, spring means to move said guides with the platen to one of said positions, and positive means to move the guides with the platen to the other position.

6. In a typewriting machine, the combination of a platen shiftable to upper and lower case positions, a guide in front of the platen, spring means to shift said guide when the platen is shifted, and positive means to return said guide when the platen is returned.

7. In a front strike typewriting machine, the combination of a platen frame and platen shiftable to upper and lower case positions, a paper guide in front of the platen, spring means to move said guide upward when the platen is shifted upward, and a rod on the platen frame having a running connection with the guide moving means for returning said guide.

8. In a typewriting machine, the combination of a shiftable platen; platen-shifting means; a work-sheet holder and guide supported entirely by the machine frame; and means separate from said shifting means to shift said holder and guide when said platen is shifted.

9. In a typewriting machine, the combination with a traveling carriage and platen, of a work sheet holder and guide coöperating with the platen, a stationary support for said holder, and means to shift the platen and said holder together in a vertical direction, said holder also shiftable independently of said shifting means.

10. In a typewriting machine, the combination of a traveling carriage, a platen frame and platen mounted therein and shiftable up and down in the carriage, a work sheet holder and guide having a stationary support, and means operated by the shifting platen frame to cause the said holder and guide to move up and down with the platen.

11. In a typewriting machine, the combination of a traveling carriage and platen, and a downwardly movable paper guide in front of the platen and projecting into the

path of travel of the carriage frame, said guide having an inclined or beveled portion to be engaged by the carriage frame to move the guide downward as the carriage approaches its limit of travel.

12. In a typewriting machine, the combination of a traveling carriage, a platen mounted therein and shiftable up and down, a work-sheet holder and guide, and spring means to move said holder and guide upward when the platen is shifted upward, said guide extending into the path of travel of the carriage frame when in said upward position, and formed to permit the frame to cam it downward.

13. In a typewriting machine, the combination of a shiftable platen frame and platen, coöperating work-sheet holders mounted independently of the platen, means operated by the platen frame to shift said holders with the platen in one direction, and springs to return the holders.

14. In a typewriting machine, the combination of a combined work-sheet holder and guide, a mount on which the said holder and guide is pivotally supported, a spring holding said guide against the platen or work-sheet, a stationary support connecting means between said support and said mount, and means to operate said connecting means for lifting and lowering the said mount as the platen is shifted.

15. In a typewriting machine, the combination of a platen shiftable to upper and lower case positions, a work-sheet holder and guide, a stationary support, bell cranks connecting said holder to said support, and means to operate said bell cranks and thereby lift and lower the holder when the platen is shifted.

16. In a typewriting machine, the combination of a platen shiftable to upper and lower case positions, work-sheet holders, bell cranks to support said holders, springs to operate the bell cranks and thereby lift the holders when the platen is lifted, and positive means connected to the platen for lowering said holders when the platen is lowered.

17. In a typewriting machine, the combination of a traveling carriage and platen, said platen being shiftable to upper and lower case positions, a work-sheet holder mounted for up and down movement when the platen is shifted, a pin carried by said holder, and a horizontal rod carried with the platen with which said pin is yieldingly held in contact.

18. In a typewriting machine, the combination of a horizontal traveling carriage, a platen frame mounted therein and shiftable to upper and lower case positions, a platen on said frame, a work-sheet holder and guide in front of the platen and mounted to shift up and down with the platen, a hori-

zontal rod connected with the platen frame, a pin or projection carried by the work sheet holder and extending beneath said rod, and a spring to move said holder upward when the platen is shifted upward thereby maintaining said projection in contact with said rod.

19. In a typewriting machine, the combination of a work-sheet holder, a stationary support, parallel links pivoted to said holder and support, and means to operate said links and thereby lift and lower said holder.

20. In a typewriting machine, the combination of a combined work sheet holder and guide, a stationary support, bell crank levers mounted on said support and connected with said holder, a link connecting said bell crank levers, and a spring to operate said levers.

21. In a typewriting machine, the combination of a platen, a work-sheet holder and guide coöperating therewith, a stationary support, parallel links connected to said support and holder, and means to effect the operation of said holder, the links being positioned to cause their pivotal points of connection with the holder to move from a position below to a position above the connection of said links with the support as the holder is lifted.

22. In a typewriting machine, the combination of a horizontal traveling carriage, a platen frame and platen, means to shift the platen frame and platen on said carriage, paper guides supported on said frame and extending transversely of the platen, horizontally disposed paper guides adapted to remain stationary during the travel of the carriage, and means operated by the platen frame for moving said last named guides up and down with the platen when the latter is shifted.

23. In a typewriting machine, the combination of a traveling carriage, a platen frame and a platen shiftable up and down in said carriage, paper guides mounted on said frame and curved to conform to the periphery of the platen, a horizontal rod connected to the platen frame and positioning said guides, and horizontally disposed guides stationary during the travel of the carriage, and movable up and down with the platen and controlled by said rod.

24. In a typewriting machine, the combination of a traveling carriage, a platen shiftable up and down therein, paper guides carried by the platen, a horizontal rod to which said guides are attached, horizontal guides stationary during the travel of the carriage, means for lifting said horizontal guides when the platen is shifted upward, and projections carried by said horizontal guides and extending beneath said rod whereby the horizontal guides are lowered with the platen.

25. In a typewriting machine, the combi-

- nation of a platen frame and platen adapted to travel in letter feed direction and also to be shifted to upper and lower case positions, and a guide for the bottom edge of a card or work-sheet, said guide operated in one direction by the shifting platen frame and maintaining a substantially constant relation to the platen during the shifting of the platen.
- 10 26. In a typewriting machine, the combination of a platen frame and platen adapted to travel in letter feed direction and also to be shifted to upper and lower case positions, and a guide for the bottom edge of a card or work-sheet, said guide being shiftable upwardly by the platen frame and spring returned and stationary during the letter feed of the platen.
- 15 27. In a typewriting machine, the combination of a platen frame and platen adapted to travel in letter feed direction and also to be shifted to upper and lower case positions, platen shifting means, a guide for the bottom edge of a card or work-sheet, means to hold the guide against the platen with a yielding pressure, and means having a running connection with the platen frame independent of said platen shifting means to shift the guide up and down with the platen.
- 20 28. In a typewriting machine, the combination with a traveling carriage and a platen frame and platen shiftable therein, of vertically disposed paper fingers connected to the platen frame and adjustable along the same to accommodate the width or position of the work-sheet, a device supporting the lower ends of said fingers, and a horizontally disposed guide adapted to shift up and down with the platen, and having its shifting movement controlled by said device.
- 25 29. In a typewriting machine, the combination with a traveling carriage, and a platen frame and platen mounted therein and shiftable up and down, of vertically disposed paper fingers supported on the platen frame and extending over the face of the platen, a horizontal rod connected to the platen frame and supporting the lower ends of said fingers, a stationary support and horizontally disposed wing guides mounted on said stationary support, shiftable up and down with the platen, and having their shifting movement controlled by said horizontal rod.
- 30 30. In a typewriting machine, the combination with a traveling carriage, a platen frame shiftable therein, a platen in said frame, vertically disposed paper guides formed of thin sheet material extending over the front of the platen, horizontal guides in front of the platen, a stationary support on which said horizontal guides are mounted, and means for shifting the horizontal guides up and down with the platen, said horizontal guides permitting the vertically disposed guides to pass behind them so that the vertical guides are brought between the horizontal guides and the platen during the travel of the carriage.
- 35 31. In a typewriting machine, the combination of a traveling carriage and platen, a non-traveling work-sheet guide extending along the platen coincident with the printing line to serve as a gage, and of a length to extend beyond the platen when the carriage is at the limit of its travel, the guide being normally in the path of a part of the carriage, and means dependent upon the movement of the carriage for moving the guide out of the way of the carriage.
- 40 32. In a typewriting machine, the combination with a traveling carriage and platen, of a non-traveling work-sheet guide extending along the platen adjacent the printing line and projecting into the path of the carriage, and a yieldable mounting for said guide to permit the latter to be moved out of the path of the carriage.
- 45 33. In a typewriting machine, the combination with a traveling carriage and platen, of a paper guide in front of the platen and projecting into the path of the carriage frame, and a yielding mounting for said guide to permit the latter to be cammed to a non-interfering position as the carriage approaches its limit of travel.
- 50 34. In a typewriting machine, the combination with a traveling carriage, a platen frame, and a platen mounted thereon and shiftable to upper and lower case positions, of a paper guide adjacent to the printing point and extending into position to project beyond the end of the carriage when the latter is at the limit of its travel, and means to shift said guide up and down with the platen, said means permitting the guide to be held down by the carriage when the guide is in said projected position and the platen shifted to upper case position.
- 55 35. In a typewriting machine, the combination with a traveling carriage and a platen thereon, of means to shift the platen to upper and lower case positions, a non-traveling paper guide, and spring means to shift the guide upwardly with the platen, said guide extending beyond the end of the carriage frame when the latter is at the limit of its travel in one direction, and being prevented by the carriage frame from moving upwardly with the platen while in said extended position.
- 60 36. In a typewriting machine, the combination with a traveling carriage and a platen shiftable to upper and lower case positions, of a non-traveling paper guide in front of the platen having its upper edge extending along the printing line, a parallel link connection between said guide and the main frame of the machine, a spring to move said guide upwardly with the platen as the

latter is shifted to upper case position, and positive means for returning the guide when the platen is returned.

37. In a typewriting machine, the combination of a traveling platen; means to shift the platen to upper and lower case positions; a guide supported entirely by the frame of the machine and stationary during the travel of the platen; and automatic means free of connection with said shifting means for raising said guide when said platen is raised.

38. In a typewriting machine, the combination with a platen shiftable to upper and lower case positions, of a line-gage extending along the face of the platen at the writing line, and means forming a running connection between the platen and gage for causing said gage to move up and down with the platen as the latter is shifted, and thereby indicate the writing line when the platen is in both upper and lower case positions.

39. In a typewriting machine, the combination with a roller platen shiftable to upper and lower case positions, of a work-piece holder mounted on the machine frame and bearing against the platen or a work-piece thereon along the line of writing, and means forming a running connection between the platen and gage permitting the gage to remain stationary during the letter-feed travel of the platen and causing said holder to shift up and down with the platen, and thereby maintain a substantially constant relation to the platen during the case-shifting movements of the latter.

40. In a typewriting machine, the combination with a platen and a set of types, said platen and types relatively shiftable to different case positions, of a line-gage extending along the writing line on the platen, and means partaking of the letter-feed movement of the platen and having a running connection with the gage for holding it at the writing line for both case positions.

41. In a front-strike writing machine, the combination with a carriage and a roller platen mounted thereon and shiftable to upper and lower case positions, of a plate having its upper edge extending along the printing line on the platen, said plate mounted to swing on the machine frame to move its said edge toward and from the platen, and means to shift said plate up and down with the platen to maintain the relative position of the platen and said plate substantially unchanged as the platen is shifted to upper and lower case positions.

42. In a typewriting machine, the combination with a roller platen shiftable to upper and lower case positions, of a combined work-piece-holder and line-gage extending along the surface of the platen at the writing line, said combined gage and

work-piece-holder mounted to swing toward and from the face of the platen, and means to cause said gage to move up and down with the platen, and thereby maintain its position relative to the platen unchanged during the case-shifting movement.

43. The combination with a carriage and a roller platen mounted thereon and shiftable to upper and lower case positions, of a type-bar segment, type-bars mounted thereon to swing upwardly and rearwardly against the face of the platen or a work-piece thereon, wings mounted on said segment on opposite sides of the printing center to swing toward and from the face of the platen, means to hold said wings with a yielding pressure against the platen or work-piece thereon, and means to shift said wings up and down as the platen is shifted to upper and lower case positions, and thereby maintain a substantially constant relative position of said wings and the platen during the case-shifting movements of the platen.

44. In a typewriting machine, the combination with a platen shiftable to upper and lower case positions, of a type-bar segment, a work-piece-holder supported on said segment, and movable up and down thereon, means to cause said work-piece holder to move up and down with the platen as the latter is shifted to upper and lower case positions, said holder movable toward and from the face of the platen, and means to cause the said holder to bear with a yielding pressure against the face of the platen or a work-piece thereon.

45. In a typewriting machine, the combination with a platen and a set of type-bars having upper and lower case types, of a support for the type-bars, said platen and support relatively shiftable for printing with the types of either case, a line-gage carried on said support and extending along the line of writing on the platen, and means carried with the platen and having a running connection with said gage to cause the gage to shift relatively to its support during said case-shifting movement and thereby maintain a substantially constant relation to the writing line during said shifting.

46. In a typewriting machine, the combination with a roller platen, of a set of type-bars having upper and lower case types, a support on which the type-bars are mounted to swing to and from the platen to cause the types to print, said platen and support relatively shiftable to enable the types of either case to print, a line-gage mounted on said support and extending along the printing line on the platen, and shifting means for said gage moving with the platen and having a running connection with the gage permitting the gage to remain stationary during the letter-feed travel of the platen,

said shifting means operable to shift the gage relatively to its support during the case-shifting movement to maintain the gage in position to indicate the line of writing for both case positions.

47. In a typewriting machine, the combination with a platen frame and platen shiftable up and down to upper and lower case positions, of a line-gage extending along the 10 face of the platen, means on the platen frame having a running connection with the line-gage to hold it at the writing line when the platen is in upper case position, and means to move said gage downward into 15 position to expose to view the writing line when the platen is shifted downward to lower-case position.

48. The combination with a roller platen having a letter-feed movement in a direction parallel with its axis, of types to print thereon, said types having a common printing center, a gage extending along the printing line and held stationary during the letter-feed travel of the platen, said platen 20

shiftable to upper and lower case positions, 25 and means moving with the platen during its letter-feed travel and case-shifting movements to move said gage with the platen as it is shifted to upper-case position, and thereby maintain the gage in position to indicate the printing line when the platen is in upper-case position.

49. The combination with a carriage and a platen mounted thereon and shiftable to upper and lower case positions, of a work-piece holder in position to bear against the face of a work-piece on the platen substantially along the printing line, and means carried with the platen to shift said holder up and down with the platen, said means 35 having a sliding connection with the holder permitting the latter to remain at rest during the travel of the carriage.

ADOLPHUS S. DENNIS.
